UNITED STATES PATENT OFFICE.

GEORGE W. ALLEN AND JOHN S. LINDSEY, OF LOUISBURG, MISSOURI.

KITCHEN-CABINET.

SPECIFICATION forming part of Letters Patent No. 452,207, dated May 12, 1891.

Application filed December 18, 1890. Serial No. 375,146. (No model.)

To all whom it may concern:

Be it known that we, GEORGE W. ALLEN and JOHN S. LINDSEY, citizens of the United States of America, residing at Louisburg, in the county of Dallas and State of Missouri, have invented certain new and useful Improvements in Kitchen-Cabinets, of which the following is a specification, reference being had therein to the accompanying drawings.

This invention relates to improvements in kitchen-cabinets, having for its object the production of a new and improved combined meal and flour chest comprising suitable means for readily and easily sifting the meal and flour, as also the provision of a lid or cover, which when inverted serves as a kneading-board, substantially as hereinafter fully set forth, and particularly pointed out in the claims.

In the accompanying drawings, Figure 1 is a front elevation slightly in perspective. Fig. 2 is a longitudinal sectional view. Fig. 3 is a detail view of one of the drawers and its sifter. Fig. 4 is a view of the invertible lid or cover.

Referring to the drawings, A designates the box or chest, divided by a central partition a into two chambers or compartments a' a^2 , the former being used for meal and the latter for flour. The lower ends of these compartments are formed into hoppers a^3 , and in their upper ends are located removable boxes or compartments a^4 , having hinged lids, said boxes being held in place by horizontal and vertical strips a^5 , secured to the walls of the chest at right angles to each other. These boxes are designed to contain salts, spices, rolling-pins, &c., and can be readily and easily removed from the chest when desired.

B is the lid or cover, which consists, preferably, of a single board having a flange or strip b at its ends and one side for fitting the front and ends of chest A, the rear portion of said lid or cover being engaged and held by angle-plates b' , secured to the rear wall of the chest and projecting above the upper edge thereof. By inserting this board and securing it in place in the same manner as when used as a lid or cover it serves as a kneading or mixing board.

C C are two drawers located beneath the hopper ends of the compartments a' a^2 . These

drawers have each a removable bottom d , which moves in parallel side boards d' d^2 , and to the upper edges of the latter are secured 55 plates d^3 , which engage grooved guide-boards d^4 , secured to the chest A. In each drawer is located a sieve or screen D, over the upper surface of which is designed to move an agitator E, consisting of a series of connected 60 bars e , one of which has a cranked portion e' , to which is secured one end of a pitman e^2 , the other end thereof being secured to a crank-shaft e^3 , journaled in the front and rear walls of the drawer. A removable crank-handle e^4 65 is designed to be connected to the front end of each crank-shaft e^3 . The agitator is guided in its movement and held down onto the sieve or screen by longitudinal rods f , secured to opposite bars of the screen-frame F. These 70 longitudinal rods are curved or bent upward at each side, as at f' , and downward at their centers f^2 to permit of the free movement of the pitman. By thus bending the wires the bran is worked above the sieve and better 75 agitation is secured generally. The drawer can be itself bodily removed from the chest, and its contents can be readily emptied by withdrawing the sliding bottom thereof. The side board d^2 is removably secured in place 80 by screws f^3 , so that the sieve or screen and its frame can be renewed when worn or damaged. By turning the crank-handle the meal or flour is easily and thoroughly sifted by the screen, and the same is removed and held in 85 the drawer until emptied.

In the meal compartment a' , just above the hopper-like end thereof, is located a horizontal slide G, which is passed through a slot or opening in the end of chest A and is guided 90 by strips g . By means of this slide a portion only of the meal is sifted at a time, since it is necessary to empty the drawer of its bran more frequently than is required for the flour-sifter.

Our invention is extremely simple and durable, and by means thereof the sifting or mixing of meal and flour can be readily and easily accomplished.

We claim as our invention—

1. The combination, with the chest having a compartment, of the drawer having a removable bottom and a removable side board, the frame secured in said drawer, the sieve

or screen, the longitudinal guide-rods connected to said frame, the agitator located beneath said guide-rods, the pitman connected thereto, the crank-shaft to which said pitman is connected, and the crank, substantially as set forth.

2. The chest having two compartments provided with lower hopper ends, the drawers having stationary sieves or screens, and the removable partition located in one of said compartments above its hopper ends, substantially as set forth.

3. In a kitchen-cabinet, the combination,

with the chest having angle-plates secured to and projecting above its rear wall, of the invertible lid or cover consisting of a flat board having a flange at its ends and front and designed to be held by said angle-plates, as set forth.

In testimony whereof we affix our signatures in presence of two witnesses.

GEO. W. ALLEN.

JOHN S. LINDSEY.
